UNITED STATES PATENT OFFICE.

ALBERT E. MCGILL, OF CHICAGO, ILLINOIS, ASSIGNOR, BY MESNE ASSIGNMENTS, TO WILLIAM S. FERRIS, OF ELKHART, INDIANA, AND ALEXANDER B. LEITH, OF CHICAGO, ILLINOIS, TRUSTEES.

FOLDING PERAMBULATOR OR BABY-CARRIAGE.

1,094,456.

Specification of Letters Patent.

Patented Apr. 28, 1914.

Application filed December 11, 1906, Serial No. 347,259. Renewed March 15, 1909. Serial No. 483,585.

To all whom it may concern:

Be it known that I, ALBERT E. MCGILL, a citizen of the United States, residing at Chicago, in the county of Cook and State of Illinois, have invented certain new and useful Improvements in Folding Perambulators or Baby-Carriages, of which the following is a specification.

This invention relates to folding perambulators or baby carriages and the object of the same is to provide an improved device of this character which may be compactly folded and which will be light, simple and durable in construction and efficient in operation.

A further object is to provide an improved adjustable back for the seat.

A further object is to provide an improved seat frame which may be adjusted into position by means of the handle and improved means for locking the frame and handle in position.

A further object is to construct an adjustable foot rest, provided with improved means for locking or securing the same into adjusted position and for automatically releasing the rest.

To the attainment of these ends and the accomplishment of other new and useful objects, as will appear, the invention consists in the features of novelty, in the construction, combination and arrangement of the several parts hereinafter more fully described, and claimed and shown in the accompanying drawings illustrating an exemplification of the invention and in which—

Figure 1 is a side elevation of a device of this character constructed in accordance with the principles of this invention. Fig. 2 is a top plan view of Fig. 1. Fig. 3 is an enlarged detail elevation of the adjustable back showing in dotted lines the back in one of its adjusted positions. Fig. 4 is a plan view on line 4—4 of Fig. 3. Fig. 5 is a detail perspective view of a portion of the guide for the sliding member and the lock or latch. Fig. 6 is a detail elevation of a portion of the frame and the foot rest, also showing the latter in dotted lines in its adjusted position. Fig. 7 is a plan view of Fig. 6. Fig. 8 is a detail view of the foot rest, lock and releasing means in operative position with respect to each other. Fig. 9

is a detail perspective view of the foot rest locking member. Fig. 10 is a detail view partly in section of the hinged connection of the seat supporting frame and the running gear frame. Fig. 11 is a detail perspective view of the hooked member which is secured to the seat supporting frame and which forms a portion of the hinge for said frame. Fig. 12 is a front elevation of Fig. 1. Fig. 13 is a side view of this improved perambulator or baby carriage, folded. Fig. 14 is a front elevation of Fig. 13. Fig. 15 is a detail rear elevation of the back supporting frame. Fig. 16 is a perspective view of one of the back supports or standards. Fig. 17 is a perspective view of one of the back supporting links. Fig. 18 is a detail view of one of the sliding members and a portion of the seat supporting frame and the main running gear frame partly in section. Fig. 19 is a perspective view of one of the sliding members. Fig. 20 is a perspective view of the locking or retaining latch.

Referring more particularly to the drawing, the same reference numerals designate similar parts throughout the several views.

In this exemplification of the invention, the main supporting or running gear frame preferably comprises spaced parallel side bars or members 25. These side bars or members may be held in their relative position in any suitable manner, preferably by means of braces 26, which are respectively pivoted to the bars or members 25 and preferably depend for some distance below said bars. These braces are preferably located adjacent the ends of said bars and are connected in any suitable manner such as by means of a bar or brace 27.

Suitable wheel forks, brackets or supports 28 may be journaled or pivoted to the side bars 25 in any suitable manner and at points 95 preferably adjacent the ends of the side bars 25. These brackets are adapted to be folded under and flat against the running gear frame and are held in their operative position, preferably by means of the bar or brace 100 27 respectively engaging the inner faces of said brackets. Secured to and extending across the front ends of these side bars is a connecting bar 29^a. The side bars 25 are preferably cylindrical in cross section but 105 the specific construction of the main sup-

porting or running gear frame, the wheel supports or brackets 28 and braces 26 and 27 form no part of the present invention.

The seat supporting frame preferably 5 comprises side bars 29, which may be hinged or otherwise connected to the cross bar 29^a in any suitable manner, preferably by means of hook-shaped members 30 which are secured to the ends of the side bars 29, the 10 hook-shaped portions of which enter suitable apertures in the cross bar 29^a. Secured to the top of the side bars 25, preferably at a point adjacent the rear thereof and in any suitable manner, such as by means of screws 15 or bolts 32, is a plate or member 33. This member is preferably of a width equal to or greater than the horizontal diameter of the side bars or members 25, so that the side edges thereof will form projecting flanges. 20 A sleeve or member 34, preferably of an inverted substantially U-shaped formation, is provided with inwardly projecting flanges or ears 35 located at the extremity of the sides of said member and said ears or flanges 25 are adapted to pass under the edges and engage the lower face of the plate or member 33 to form a sliding engagement with said plate or member. A guide or member, comprising a body portion 36, is provided with 30 downwardly projecting flanges 37 at the extremities thereof and a projecting foot or member 38^a at the base of each of the depending flanges. These guides or members are secured over and preferably parallel 35 with the plates or members 33 and are held in position preferably by means of the screws or bolts 32 which pass through the portions 38^a and which serve to hold the plates or members 33 in position. This 40 guide or member 36 is spaced from the plate or member 33 to permit the member 34 to slide freely on the plate or member 33. A suitable bar 37^a extends across the main running gear or supporting frame and the extremities thereof pass loosely through suitable apertures in the sliding member 34. Mounted loosely upon the bar 37^a adjacent the members 36 are sleeves or collars 39 which are preferably offset from the bar 37^a, 45 as shown more clearly in Fig. 4. Loosely supported by the sleeves or collars 39 and by one end thereof, are supports or standards 40, which project for some distance above the main supporting or running gear frame. The upper or free ends of these supports or standards 40 are pivotally connected to sleeves or collars 41, which latter are secured in any desired manner preferably by means of screws or bolts 42 to the free 50 extremities of the side bars 29 of the seat supporting frame; so that when the members 34 are slid or moved upon the main supporting or running gear frame, the side bars 29 of the seat supporting frame will be raised 60 or lowered according to the direction of

movement of the members 34, which movement will be permitted by means of the pivotal connection of the sleeves or collars 39 with the bar 37^a and of the support or standard 40 with the sleeve or collar 41.

70

Any suitable means may be provided for locking the members 34 in a position to hold the free ends of the side bars 29 of the seat supporting frame in an elevated position, and an efficient device for this purpose 75 will now be described. A suitable latch comprising a body portion 43 is constructed of a thin strip of metal arranged on edge and projecting laterally from one extremity thereof are lugs 44. A laterally projecting 80 portion 45 is arranged at the other extremity of the body portion and projecting forwardly from the free extremity of said offset portion 45 is an ear or lug 46, which latter is preferably provided with 85 an aperture 47 passing transversely therethrough. The body portion of the guide 36 is provided with a longitudinal slot 48, one extremity,—preferably the end adjacent the front of the main supporting or running gear frame—is enlarged as at 49. The body portion 43 of the latch is adapted to pass through the longitudinal slot 48 of the guide 36 so that the offset portion 45 will rest upon the upper face thereof. A suitable bearing 50 is secured to the 90 upper face of the guide 36 adjacent the enlarged portion 49 of the slot 48 in which the laterally projecting lugs 44 are journaled. The free extremity of the projecting ear or lug 46 is adapted to pass over the connecting bar 37^a and project toward the rear of the main supporting or running gear frame and the extremities of these projecting ears are connected in any suitable 95 manner, preferably by means of a cross bar 50^a extending transversely across the main supporting or running gear frame.

95

A suitable handle 51 is pivotally supported by one end to the main frame, preferably by means of a bolt or rod 52, extending transversely across the frame. An operating treadle 53 is pivoted between its ends to said cross bar 52; one end of this treadle preferably projects beyond the rear of the main frame and the other end is loosely connected to the transverse bar 50^a, so that when the projecting free extremity of the treadle is depressed the other end of said treadle will raise the transverse bar 50^a, thereby simultaneously raising the latches or locking members 43. Bars or links 54 are pivotally connected by one end to the handle 51 and by the other end to the members 34, preferably by means of one end of the bar 37^a 125 passing through a suitable aperture in said links or bars 54 and the latter are held in position by means of suitable nuts 55^a engaging the extremities of the bars 37^a. The latches or members 43 are of such a length 130

that when the sliding members 34 assume their extreme rear position; that is, when the handle 51 is in operative position and the supports or standards 40 of the seat supporting frame are in an upright position, 5 the free ends thereof will assume a position in front of the said sliding members 34 to lock said members in position. The latches 43 are normally depressed by suitable 10 springs 55, which are preferably secured to the guide 36 and rest upon the tops thereof. The springs 55 are of such a tension that when it is desired to unfold the carriage in a manner to be more fully set forth, the 15 members 34 will engage the lower faces of the latches 43 and raise the latter against the tension of the springs and said latches will return to their normal position when the members 34 have assumed the position, as 20 shown more clearly in Figs. 1 and 3 of the drawings.

A bar or member 56, provided with side arms 57, is arranged between the supports or standards 40, the extremities of said arms 25 being preferably laterally deflected as at 58 and loosely engage the supports or standards. These extremities preferably surround the standards and are held in position relative thereto in any suitable manner, such as by means of pins or bolts 59 30 passing through the supports or standards 40 above and below the extremities 58. Secured to the bar or member 56, preferably to the lower face thereof, adjacent the side 35 arms 57 and by one end thereof, are substantially U-shaped springs or yielding members 60. The free extremities thereof are provided with sleeves or collars 61 which loosely surround the bar 37^a and serve as a 40 yielding support for the seat frame. Pivotaly connected by one end to the side arms 57 of the bar or member 56 are supports or standards 62, which extend for some distance above the upper extremities of the supports or standards 40 and connecting the 45 upper extremities of the supports or standards 62 is a cross bar 63 to form a frame for the back. One face of these supports or standards 62, preferably the rear face, is 50 provided with a plurality of notches 64 and the upper extremities thereof are also provided with a notch or recess 65. Links 66 are pivotally connected to the supports or standards 40, preferably by means of collars 67 which surround said supports or standards 40 and to which one end of the 55 links 66 are pivoted. These links are preferably located adjacent the outer face of the supports or standards 62 and surrounding 60 the latter is a substantially U-shaped member 68, the extremities 69 of which are secured to the free ends of the links 66. The upper extremity 69 of this U-shaped member is adapted to be seated in either of the 65 notches 64 or 65 to permit the back frame

to be raised or lowered and supported at the desired inclination. Suitable laterally extending lugs or projections 70 are arranged on the supports or standards 62 preferably below the lowest notch 64 and serve as a 70 means for preventing displacement of the links 66 when the back frame is adjusted to its extreme lowest position, as shown more clearly in dotted lines in Fig. 3.

The seat proper 71 is preferably constructed of suitable flexible material, such as leather, canvas, duck or the like, and formed into the desired shape. The upper extremities of the sides thereof are secured to the side bars 29 of the seat supporting frame in 75 any suitable manner, preferably by means of bars or members 72 to which the extremities may be secured and said bars are secured to the side bars 29, preferably by means of a collar or sleeve 73 to which one end of the 80 bars 72 are secured, the other extremities of which are secured in position in any suitable manner, preferably by means of the sleeves or collars 41 at the free extremities of the side bars 29. The back 74 of the seat may be 85 formed integrally therewith and is of sufficient length to loosely engage the cross bar 63 between the supports or standards 62, so that when the back frame is lowered to the 90 position shown in dotted lines in Fig. 3, the 95 back 74 will not interfere with the free movement thereof. The foot support 74^a may be also formed integrally with the body portion 71 and the free extremity of this support is loosely secured to a substantially 100 U-shaped bar 75. The extremities 76 of the side arms 77 of the bar 75 are preferably bent into L-shaped portions and said portions are connected for sliding movement with the ends of the side bars 29 of the seat 105 supporting frame in any suitable manner preferably by means of a guide 78, the extremity of the offset portions 76 being deflected slightly downward, as more clearly shown in Fig. 6 of the drawing, to prevent 110 lateral displacement of the supporting bar 75. Pivotaly connected by one end to the bar 75, preferably at the junction of the side arms 77 therewith, are links 79. The free 115 ends of these links are preferably provided with elongated slots 80, the inner extremities of said slots being offset as at 81 to form a shoulder 82 and these extremities of the links are pivotally connected to the inner faces of the side bars 29 of the seat supporting frame 120 in any suitable manner, preferably by means of headed screws or bolts 83 passing through said slots and into the side bars 29 so that the ends of the links will have a sliding connection with the side bars 29. In their normal position or with the parts as shown in full lines in Fig. 6, the links 79 will be substantially parallel, with the side bars 29 and with the outer extremities of the slots 80 resting against the screws or bolts 83. In 125 130

this position the deflected extremities 76 of the side arms 77 of the bar 75 will rest against the inner end of the guide 78 adjacent the extremity of the links and serve to hold the foot rest in position. When it is desired to adjust the foot rest to the position shown in dotted lines in Fig. 6, the operator raises the bar 75. This movement of the bar will cause the links 79 to turn about their pivots and at the same time the slotted extremities will slide on the screws or bolts 83 until the offset portion 81 in the slot assumes a position to drop over the said screws or bolts. The deflected portion 76 of the side arms 77 will be moved downwardly toward the end of the side bars 79 until said portion engages the shoulder 84 formed adjacent the other end of the guide 77 and will support the bar 75 in the position shown in dotted lines in Fig. 6. With the foot rest thus elevated and the back 74 of the seat lowered to the position shown in Fig. 3, the occupant may assume a comfortable reclining position.

When it is desired to lower the foot rest to the position shown in full lines in Fig. 6, the operator simply moves the side arms 77 of the bar 75 to cause the extremities 76 thereof to slide in the guide 78 toward the links 79 until said extremities contact with the extremities of the links 79, as shown more clearly in Fig. 8 of the drawing. A further movement of the arms 77 in the same direction will raise the notch or offset portion 81 of the slot 80 out of engagement with the screws or bolts 83 to unlock the links 79. When the links are thus unlocked they may be drawn outwardly until the ends of the slots engage the screws or bolts 83 when the links 79 may be turned upon the pivot thus formed to assume their normal position.

It is thought that the operation of the remaining portion of this improved perambulator or baby carriage will be fully understood but briefly stated, it is as follows: Assuming the seat supporting frame, the back thereof and the handle 51 to be in the position shown in full lines in Figs. 1 and 3, and it is desired to fold the perambulator, the operator simply depresses the free extremity of the treadle 53, which operation will raise the latches 43 out of engagement with the sliding members 34. The handle 51 may be then turned about its pivot and through the medium of the connecting links 54 will slide the members 34 toward the forward end of the main supporting or running gear frame. As the members 34 move forwardly, the supports or standards 40 will turn about their pivots, thus lowering the seat supporting frame. As the seat supporting frame is lowered, the springs 60 will be rotated about the bar 37^a by means of the sleeve 61. The links 66 may be adjusted to permit the back supporting frame to be lowered and when the frame is in its lowered

position, the supports or standards 62 may be turned about their pivots and folded down upon the top of the seat supporting frame. After these parts have assumed this position, the handle 51 may be moved further forward about its pivot so as to rest upon the main supporting or running gear frame, as shown more clearly in Fig. 13. The parts may be adjusted to an operative position by reversing the operation just described.

It will thus be seen that with such a construction a light, simple and durable perambulator will be produced; the seat supporting frame being permitted to move about its point of pivotal support to accommodate the weight of the occupant by means of the springs or yielding members 60 and the loose connection of the supports or standards 40 with the sleeves 39. The angle of inclination of the back may be also varied by engagement of the U-shaped members 68 with the various notches 64 in the supports or standards 62, as will be understood.

In order that the invention may be fully understood the details of an embodiment thereof have been thus specifically described.

What I claim is:—

1. In a device of the class described, the combination of a running gear frame containing spaced side bars, guides secured to the bars, members movable in the guides, a body structure pivoted by one end to the running gear frame, supports pivoted by one end to the members and by the other end to the free end of the body structure, a pivoted handle, and links connecting the handle and the members for moving the latter in the guides when the handle is moved about its pivot to raise and lower the free end of the body structure.

2. In a device of the class described, the combination of a running gear frame containing spaced side bars, guides secured to the bars, members movable in the guides, a body structure pivoted by one end to the running gear frame, supports pivoted by one end to the members and by their other end to the free end of the body structure, a pivoted handle, means controlled by the movement of the handle adapted to move the members in the guide for raising and lowering the body structure, and yielding latches projecting into the guides and adapted to assume a position in front of the members to lock the body structure in position.

3. In a device of the class described, the combination of a running gear frame containing spaced side bars, members secured to the bars and projecting beyond the sides thereof, a pivoted body structure, inverted substantially U-shaped members, provided with inwardly projecting flanges at the extremities of the sides thereof, said members

being adapted to surround the first said members so that the flanges will pass under the edges thereof, supports pivotally connected to the second said members, and the 5 body structure, a pivoted handle, and means controlled by the handle adapted to move the second said members on the first members to raise and lower the body structure.

4. In a device of the class described, the 10 combination of a running gear frame, containing spaced side bars, members secured to the bars and projecting beyond the sides thereof, guides secured over and spaced from said members, a foldable body structure, inverted substantially U-shaped members, provided with inwardly projecting flanges at the extremities of the sides thereof, said members being adapted to surround the first said members so that the flanges 15 will pass under the edges thereof and being disposed between said members and the guides, supports pivotally engaging the second said members and the said body structure, a pivoted handle, and means controlled 20 by the handle adapted to slide the U-shaped members on the first said members for folding and unfolding the body structure.

5. In a device of the class described, the 25 combination of a running gear frame, containing spaced side bars, members secured to the bars and projecting beyond the sides thereof, guides secured over and spaced from said members, a foldable body structure, inverted substantially U-shaped members, provided with inwardly projecting flanges at the extremities of the sides thereof, said members being adapted to surround the first said members so that the flanges will pass under the edges thereof and being 30 disposed between said members and the guides, supports pivotally engaging the second said members and the said body structure, a pivoted handle, means controlled by the handle adapted to slide the U-shaped 35 members on the first said members for folding and unfolding the body structure, and means passing through the guides and adapted to engage the sliding members to lock the body structure in position.

6. In a device of the class described, the 40 combination of a running gear frame, containing spaced side bars, members secured to the bars and projecting beyond the sides thereof, guides secured over and spaced 45 from said members, a foldable body structure, inverted substantially U-shaped members, provided with inwardly projecting flanges at the extremities of the sides thereof, said members being adapted to surround 50 the first said members so that the flanges will pass under the edges thereof and being disposed between said members and the guides, supports pivotally engaging the second said members and the said body structure, a pivoted handle, means controlled by 55

the handle adapted to slide the U-shaped members on the first said members for folding and unfolding the body structure, latches passing through the guides and adapted to engage the sliding member to 60 lock the frame in position and means for simultaneously releasing said members. 70

7. In a device of the class described, the combination of a running gear frame, a 75 folding body structure, a folding handle, deflectable braces for the body structure, said structure embodying an independently adjustable back, operatively related to the braces, means for yieldingly supporting the body structure, means for moving the braces 80 and support into position by the operation of the handle and means for locking said parts in position.

8. In a device of the class described, the combination of a running gear frame, a 85 folding body structure supporting frame, members mounted for sliding movement on the frame, a connection between the members, braces pivotally connected by one end to the connection, and by the other end to 90 the body structure, a member secured between the braces, a back frame, pivotally connected by one end to the last said member, and means for independently adjusting the back. 95

9. In a device of the class described, the combination of a running gear frame, a folding body structure, members mounted for sliding movement on the frame, a connection between the members, braces pivotally connected by one end to the connection and by the other end to the body structure, a member secured between the braces, a back frame pivotally connected by one end to the last said member, said frame containing 100 notched standards, and links pivotally connected to the body structure and adapted to engage the notches in the standards for adjusting the back frame. 105

10. In a device of the class described, the 110 combination of a running gear frame, a folding body structure, members mounted for sliding movement on the frame, a connection between the members, braces pivotally connected to the members and the body 115 structure, a member secured between the braces, a back frame pivotally connected by one end to the last said member, means for adjusting said back frame, yielding members, one end of which is secured to the connecting member between the braces and the other ends having a loose connection with the connection between the first said members, a pivoted handle and means for moving the body structure and braces by the 120 operation of the handle. 125

11. In a device of the class described, the combination of a running gear frame, a folding body structure, members mounted for sliding movement on the frame, a connec- 130

- tion between the members, braces pivotally connected to the members and the body structure, a member secured between the braces, a back frame pivotally connected by 5 one end to the last said member, means for adjusting said back frame, yielding members, one end of which is secured to the connecting member between the braces and the other ends having a loose connection with 10 the connection between the first said members, a pivoted handle, means for moving the supporting frame and braces by the operation of the handle and a lock for holding the braces and frame in position.
- 15 12. In a device of the class described, the combination of a running gear frame, a folding body structure, braces having pivotal connection with the body structure, and sliding and pivoted connection with the running 20 gear frame, means for yieldingly supporting the body structure, said structure embodying a back frame, pivotally related to the last said means, means for independently adjusting said back frame, means for 25 moving the body structure and support by the operation of the handle, and an independently adjustable foot rest supporting frame.
13. In a device of the class described, the 30 combination of a running gear frame, a folding body structure, deflectable braces for the said structure, a pivoted handle, means for adjusting the body structure by the operation of the handle, said body structure embodying an independently adjustable back 35 frame, a foot rest supporting frame, and means for supporting the last said frame in its adjusted position said means being adapted to release the foot rest frame.
- 40 14. In a device of the class described, the combination of a running gear frame, a folding body structure, deflectable braces for the said structure, a pivoted handle, means for adjusting the body structure and braces 45 by the operation of the handle, a foot rest supporting frame, comprising a cross bar mounted by its ends for sliding and pivotal movement on the seat frame, links pivotally connected by one end to the bar and having 50 sliding and pivotal connection by its other

end to the body structure for adjusting the foot rest frame, and means for locking said foot rest frame in its adjusted position.

15. In a device of the class described, the combination of a running gear frame, a folding body structure, deflectable braces for the said structure, a pivoted handle, means for adjusting the body structure and braces by the operation of the handle, a foot rest supporting frame, comprising a cross bar mounted by its ends for sliding and pivotal movement on the seat frame, links pivotally connected by one end to the bar and having sliding and pivotal connection by the other end to the body structure for adjusting the foot rest frame, and means for locking said foot rest frame in its adjusted position, the ends of said bar being adapted to engage the links for releasing the same to permit the foot rest frame to be adjusted. 55 60 65 70

16. In a device of the class described, the combination of a running gear frame, a folding body structure, a pivoted handle, means for adjusting the body structure by the operation of the handle, an independently adjustable foot rest frame, comprising a cross bar provided with side arms, guides on the body structure in which the ends of the arms are slidingly and pivotally mounted, links, one end of which is pivotally connected to the bar, the other ends being provided with slots having an offset portion, and lateral projections on the body structure extending into the slots, said links and bars being adapted to be adjusted to permit the projections to enter the offset portion of the slots for supporting the frame in an adjusted position, the ends of the arms being adapted to engage the links to disengage the offset portions and projections to 80 85 90 release said frame.

In testimony whereof I have signed my name to this specification, in the presence of two subscribing witnesses, on this 28th day of November, A. D. 1906.

ALBERT E. MCGILL.
